UNITED STATES PATENT OFFICE

2,471,103

WATCH MOVEMENT HOLDER

David Franks and Morris Shapiro,
Washington, D. C.

Application July 26, 1945, Serial No. 607,160

2 Claims. (Cl. 81—6)

1

The present invention relates to improvements in watchmakers' tools and has reference more particularly to a watch movement holder.

One of the important objects of the present invention is to provide a watch movement holder that is capable of accommodating various sizes and shapes of watch movements and which hold the same securely and conveniently while undergoing inspection and repair.

A further object of our invention resides in the provision of a watch movement holder that does not require any mechanical adjustment in order to accommodate various sizes of watch movements.

A still further object is to provide a watch movement holder that will securely engage and support the watch movement in such a manner that the parts of the watch movement will be readily and easily accessible for repair and replacement without interfering with the operating parts of the holder.

Another object of importance is to provide a watch movement holder that includes means for positive locking engagement with the lateral flange of the watch movement thus preventing any slippage or casual disengagement of the watch movement when positioned on the holder.

A still further object is to provide a watch movement holder that consists of relatively few parts, thus rendering the same inexpensive in its manufacture and readily and easily operable.

Other objects and advantages of this invention will become apparent from the following description, when taken in connection with the accompanying drawing.

In the drawing forming a part of this specification and wherein like reference characters designate corresponding parts throughout the several views:

Figure 1 is a side elevation of our watch movement holder, showing a watch movement engaged and supported thereon;

Figure 2 is a top plan view of the holder;

Figure 3 is a longitudinal sectional view taken approximately on the line 3—3 of Figure 2;

Figure 4 is a vertical sectional view taken on the line 4—4 of Figure 3, and

Figure 5 is a similar sectional view taken on the line 5—5 of Figure 3.

In the drawing, wherein for the purpose of illustration, is shown the preferred embodiment of our invention, the numeral 1 designates generally the improved watch movement holder. This holder comprises a flat metal base plate 2 having downwardly extending leg portions 3 and 4 at its respective ends.

A pair of spaced longitudinally extending slots 5 and 6 are formed in the base plate 2, as clearly illustrated in Figure 2 and the purpose thereof will be presently apparent.

2

An elongated rod 7 is slidably disposed through registering openings provided therefor in the leg portions 3 and 4. An actuating knob 8 is arranged on the forward end of the rod 7.

5 A block 9 is adjustably secured on the slidable rod 7 by means of the set screw 10 and this block engages with the underside of the base plate 2 for movement therealong.

A coil spring 11 encircles the intermediate portion of the slidable rod 7 and is interposed between the rear leg portion 3 and the adjacent face of the block 9 for normally urging the rod and block forwardly. Suitable washers 12 and 13 are arranged on the rod for cooperation with the respective ends of the coil spring and the rear leg portion and block respectively.

Extending upwardly from the front part of the base plate 2 are the stationary pins 14 and 15. These pins may be attached to the base plate in any suitable manner and in the instant case they are shown as being riveted to the base plate, although we do not desire to be limited to the particular manner in which these pins may be secured.

10 25 These pins are located between the forward ends of the respective slots in the base plate and the forward end of the latter and in alignment with the respective slots, as is clearly illustrated in the drawing.

30 The upper ends of these stationary pins are reduced and undercut to form the shoulders 16 and the beaded studs 17.

A similar pair of pins 18 and 19 are removably secured to the top of the block 9 by suitable 35 screw threaded shanks 20 and 21 that extend downwardly from these last mentioned pins through the respective slots 5 and 6 and threaded into suitable sockets provided therefor in the block 9.

40 The pins 18 and 19 constitute slidable members that move across the top face of the base plate simultaneously with the movement of the slid able push rod 7 and the block 9 carried thereby.

The pin 18 travels across the slot 5 and the 45 pin 19 moves along the other slot 6. These movable pins 18 and 19 cooperate with the stationary pins 14 and 15, respectively, in the manner to be presently described.

The upper ends of the movable pins are also 50 reduced and undercut, similar to the upper ends of the stationary pins 14 and 15 to form the shoulders 22 and the beaded studs 23.

In use, the knob 8 is pushed rearwardly, causing the spring 11 to be compressed and simultaneously moving the pins 18 and 19 away from the pins 14 and 15, thus permitting a watch movement of any shape or size to be positioned between the coacting beaded studs carried by the four pins, with the lateral flange *a* uniformly 55 60 provided in the watch movement *b* resting on

the shoulders 16 and 22 of the respective pins and the beaded studs contacting the adjacent peripheral portions of the watch movement.

When the watch movement has been properly positioned on the shoulders, pressure on the knob 8 is released, causing the spring 11 to move the rod, block and movable jaws in a forward direction, thus assuring the watch movement being securely engaged and held between the pins of the holder.

With the watch movement supported on the holder, the same may be placed on a table or other support to permit the necessary repairs and replacements made to the watch movement, and this without any interference with the operating parts of the holder.

To release the watch movement from the holder, it is only necessary to push rearwardly on the knob and instantly, the movable pins are moved away from gripping engagement with the watch movement, thereby permitting the same to be readily and easily removed.

It will thus be seen from the foregoing description that we have provided a watch movement holder that is capable of accommodating various sizes and shapes of watch movements and due to its simplicity can be readily and easily operated. Further, our device will be inexpensive, strong and durable and at all times positive and efficient in carrying out the purpose for which it has been designed.

While we have shown the preferred embodiment of our invention, it is to be understood that various changes in the size, shape and arrangement of parts may be resorted to without departing from the spirit of the invention and the scope of the appended claims.

Having thus described our invention, what we claim is:

1. A watch movement holder comprising a base plate, leg portions depending from the end portions thereof, said base plate having longitudinal slots formed therein, a pair of stationary pins extending upwardly from the base plate adjacent one end of the respective slots, a pair of coating movable pins operable through the respective slots in the base plate, means on the upper ends of

the pins for engaging and supporting a watch movement, a slidable rod extending through said leg portions, a block secured on said rod, said movable pins being mounted on the block, and spring means associated with the rod and holder for normally urging the movable pins toward the stationary pins.

2. A watch movement holder comprising a base plate, leg portions depending from the end portions thereof, said base plate having longitudinal slots formed therein, a pair of stationary pins extending upwardly from the base plate adjacent one end of the respective slots, a pair of coating movable pins operable through the respective slots in the base plate, reduced beaded studs formed on the upper ends of the pins for engaging and supporting a watch movement, a slidable rod extending through said leg portions, a handle on one end thereof, a block adjustably secured on the rod and underlying the base plate, said movable pins being mounted on the block, and a coil spring encircling the rod and disposed between one leg portion and the block for normally urging the movable pins toward the stationary pins.
